US00D546497S

(12) **United States Design Patent** (10) **Patent No.:** **US D546,497 S**
Lehman et al. (45) **Date of Patent:** **** Jul. 10, 2007**

(54) **TRANSFORMER**

(75) Inventors: **Gregg Lehman**, Peachtree City, GA (US); **Steen Vann**, Morrow, GA (US)

(73) Assignee: **Cooper Technologies Company**, Houston, TX (US)

(**) Term: **14 Years**

(21) Appl. No.: **29/252,050**

(22) Filed: **Jan. 18, 2006**

Related U.S. Application Data

(63) Continuation of application No. 29/233,364, filed on Jun. 30, 2005.

(51) **LOC (8) Cl.** **26-99**

(52) **U.S. Cl.** **D26/138**

(58) **Field of Classification Search** D26/138, D26/63, 66, 89, 24, 46, 60, 61, 72, 76, 80, D26/81, 83, 88, 90, 113, 140, 141, 142, 143, D26/149, 152, 153, 155; 362/648, 130, 217, 362/219, 220, 221, 225, 646, 649, 659, 227, 362/232, 257, 277, 285, 362, 368, 370, 371, 362/374, 382, 388, 418; 248/214; 439/118; D13/110

(57) **CLAIM**

The ornamental design for a transformer, as shown and described.

DESCRIPTION

This application is related to co-pending applications: Ser. No. 11/322,837, filed Dec. 30, 2005 and titled “Halo Flex Track”; Ser. No. 11/324,099, filed Dec. 30, 2005 and titled “Halo Power Supplies”; Ser. No. 11/323,231, filed Dec. 30, 2005 and titled “Halo Clam Shell Connections”; and Ser. No. 11/323,755, filed Dec. 30, 2005 and titled “Halo Hubs and Connections”.

FIG. 1 is a top, front perspective view of a first embodiment of a transformer showing our new design;

FIG. 2 is an open, top front perspective view thereof;

FIG. 3 is a front view thereof;

FIG. 4 is a rear view thereof;

FIG. 5 is a right side view thereof;

FIG. 6 is a left side view thereof;

FIG. 7 is an open left side view thereof;

FIG. 8 is a top view thereof;

FIG. 9 is a bottom view thereof;

FIG. 10 is a top, front perspective view of a second embodiment of a transformer showing our new design;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken lines form no part of the claimed design.
